(57) **CLAIM**

The ornamental design for the slide fastener with angled elements, as shown and described.

DESCRIPTION

FIG. 1 is a top perspective view showing my new design;
 FIG. 2 is another top perspective view of the slide fastener of FIG. 1;
 FIG. 3 is another top perspective view of the slide fastener of FIG. 1;
 FIG. 4 is an end perspective view of the slide fastener of FIG. 1; and,
 FIG. 5 is a top view of the slide fastener of FIG. 1.
 The broken lines form no part of the claimed design.
